UNITED STATES PATENT OFFICE.

FRANCES BOEHME, OF CHICAGO, ILLINOIS, ASSIGNOR TO ESTELLA LIPMAN, OF CHICAGO, ILLINOIS.

GARMENT.

Original application filed September 21, 1925, Serial No. 57,695. Divided and this application filed October 1, 1925. Serial No. 59,797.

This invention which has to do generally with a supporting undergarment is concerned more particularly with the construction of a free edge thereof whereon fasteners of any approved kind are secured. For its objects I have aimed to provide in such a garment a reinforced edge capable of holding securely any number or kind of fasteners that may be affixed thereto; means associated with such an edge for underlying the complementary free edge of the garment whereon co-operative fasteners are carried, whereby to provide a neater and more comfortable connection; and means interposed between the fasteners and the body for protecting the latter against contact and sharp pressure from the former. The improvements of this invention were earlier disclosed in my application filed September 21, 1925, Serial No. 57,695, of which this is a division.

In the description to follow reference is made to the accompanying drawing wherein an illustrative garment is shown in the manner following:

Figure 1 is a plan or development of a girdle-brassière having a free edge constructed according to my invention;

Fig. 2 is an enlarged fragmentary detail of the garment edge, showing one of the fasteners applied thereto;

Fig. 3 is a section therethrough on line 3-3 of Fig. 2;

Fig. 4 which is a view similar to Fig. 2 shows a slightly modified construction; and

Fig. 5 is a section therethrough on line 5-5 of Fig. 4.

The garment herein shown comprises girdle and brassière portions which may consist of any desired number of fabric pieces or sections suitably secured together. In the illustrative structure the front portion A may be made of any appropriate fabric. In the two garment sides are elastic gores B, and in the back or rear portion I have also shown an elastic gore C. The garment may be of the side fastening type, as shown, although the place of fastening is relatively inconsequential to this invention. To the front garment portion I have connected sections 10 of inelastic material, and similar sections 11 are also interposed between the back and side sections. A garment so con-

structed has its several components so formed and assembled as to fit desirably upon the figure. The elastic gores, all of which are vertically disposed, are suitably cut and fitted in place to improve the fit of the garment and also the comfort in wear thereof.

The garment illustrated by way of exemplification is of the side fastening type. The fasteners may take the form of hooks 12 arranged upon one free edge of the garment for cooperation with eyes 13 which are arranged upon the other free edge 14 thereof. I reinforce the free edge of one side gore B with a binding 15 which extends around to overlie the opposite sides thereof. Associated with this binding is a tape 16 having one edge 17 turned upon itself to provide a double thickness, as shown. Between the tape and binding are arranged one set of fasteners—the eyes 13, for example—each secured in place, if desired, with an eyelet 18. As by means of stitching 19, both tape plies, the fasteners, the binding, and elastic garment edge, are mutually connected. By this construction the tape is extended past the fasteners to underlie the other free edge 80 of the garment, thereby providing a neater and closer connection therewith. The fasteners are also concealed and held from contact with the body or any undergarment thereon, thus conducing to comfort in wear.

Referring now to Figs. 4 and 5, I have shown in detail a construction very similar to that which has already been described. The garment edge 14 is reinforced with a binding 15 similar to that elsewhere illustrated. Extending past the garment edge is a strip 20 which may be secured by stitching as at 21. Between this strip and the binding are arranged fasteners 13 which may have an eyelet connection 18 with the former. Applied over the outer side of the strip is a tape 22 having preferably a width which is sufficient to extend past the binding and most of each fastener as well. To complete the construction, a suitable stitching 23 may be employed, which proceeds lengthwise of the garment edge in double rows, one to each side of the fasteners, as shown in Figure 4.

It is to be noted that in each of the two forms of my invention herein shown, the fasteners are carried on a strip or tape to

which connection may be made as with eyelets. Additionally, however, this same strip or tape, or an associated element, extends across all the fasteners so as to conceal the same and protect the wearer from contact therewith. In this manner the garment is rendered more comfortable to wear.

I claim:

- 10 1. A body garment having two free edges adapted for connection, a binding reinforcing one garment edge, a tape associated with the binding and extending beyond the same, fasteners disposed between said tape and said binding, eyelets securing said fasteners to said tape, said tape having an overlying portion covering said eyelets, and other

cooperative fasteners carried by the other garment edge.

2. A body garment having two free edges 20 adapted for connection, a binding reinforcing one garment edge, a tape having one turned edge associated with the binding and extending beyond the same, fasteners disposed between said tape and said binding, eyelets securing said fasteners to said tape 25 and disposed beneath said turned edge of said tape, stitching connecting said turned edge, tape, fasteners, and binding, and other cooperative fasteners affixed to the other garment edge.

FRANCES BOEHME.
